PACKING ARTICLE FOR FRAGILE MATERIALS

Ernest L. Shepard, Fairfield, Maine, assignor to Keyes Fibre Company, Portland, Maine, a corporation of Maine

Application July 9, 1951, Serial No. 15,790

Term of patent 14 years

(Cl. D58—13)

To all whom it may concern:

Be it known that I, Ernest L. Shepard, a citizen of the United States, residing at Fairfield, in the county of Somerset, State of Maine, have invented a new, original, and ornamental Design for Packing Article for Fragile Materials, of which the following is a specification, reference being had to the accompanying drawing, forming part thereof.

Fig. 1 is a top plan view of a packing article for fragile materials, showing my new design;

Fig. 2 is a side view thereof; and

Fig. 3 is an end edge view thereof, partly in section.

I claim:

The ornamental design for a packing article for fragile materials, as shown.

ERNEST L. SHEPARD.
